[57] CLAIM

The ornamental design for a six-way spider fitting for a filter system, as shown and described.

DESCRIPTION

FIG. 1 is a perspective view of a six-way spider fitting for a filter system, according to the present invention.

FIG. 2 is a top plan view of the six-way spider fitting for a filter system.

FIG. 3 is a bottom plan view of the six-way spider fitting for a filter system; and,

FIG. 4 is a front elevation view of the six-way spider fitting for a filter system, the fitting having a symmetrical opposite rear elevation appearance, and a similar appearance in side elevation view at a view point 60° from that shown.

The broken line showing of environment in the drawings is for illustrative purposes only and forms no part of the claimed design.
